ABSTRACT

A soap holder formed of a slick suitable material of a shape to hold a conventional or oversize bar of soap. The holder includes a generally rectangular base creased at its center line to form a shallow V-shape, a pair of legs at the side edges of the base and of such configuration that the center-creased base is forwardly inclined thus forming a slanted trough for rapid run-off of water and soap suds automatically into a wash basin, and a bar soap retainer formed of at least one flange extending upwardly from the base and spaced from at least a portion of the base at its center line to allow for water run-off.

9 Claims, 8 Drawing Figures

SOAP HOLDER

BACKGROUND AND SUMMARY OF THE INVENTION

In most instances, present-day bathroom and kitchen sinks have some form of bar soap holder or receptacle; a common type consisting of a depression in a ledge or shelf surrounding the sink of a size and shape to retain a bar of soap and a narrow channel extending from the depression or recess to the basin to allow for the run-off of soapy water accumulated from the soap and hands during washing under running water or with the basin partially filled. However, sufficient water is retained in the depression to preclude drying of the soap between washings and to soften and allow abrasion or erosion of the soap.

Many solutions have been offered without fully solving the problem. A rectangular piece of sponge or pad of absorbent material has been utilized in the basin recess or depression to soak up excess water and soap suds and to provide a rest for the soap bar. However, the soap tends to stick to the pad and softened soap wears off onto the pad, and the accumulated water and soap must periodically be rinsed out of the pad.

Soap dishes have been used to prevent unsightly run-off and soap scum accumulation; however, liquid builds up in the dish and, even when the dish has one or more drain openings, the soap scum clogs the holes and the excess liquid softens and dissolves the soap bar. Also, recessed soap dishes for bath tubs and soap dishes with ejecting means have been tried but found to be inefficient.

A further attempt to overcome these problems has resulted in a soap rest which has a number of projections on which the soap rests spaced from a base or in a V-shaped cradle formed of a pair of lattice work shelves positioned at an angle to each other and joined at a common centerline. However, these members allow the water drippings and soft soap scum to fall down through the holder onto the sink flat surface or soap depression. Another type of holder utilizes a plurality of small suction cups to hold the soap away from a base portion. However, the myriad suction cups each tends to scrape and suck away the wet soap much faster than through normal use. The present invention obviates all of these problems.

Among the objects of the present invention is the provision of a novel soap holder which will provide a rapid and directed flow of water and watery soap suds from the hands, the holder and soap bar into the tub, sink or basin bowl without accumulating on a shelf or in a recess formed on the basin. The holder forms a trough of a wide V-shape which is inclined downwardly and forwardly and promotes water run-off, and the up-standing retaining member are spaced from the centerline of the trough so as not to hinder water flow.

Another object of the present invention is the provision of a novel soap holder which substantially prevents undue erosion of the soap bar and permits rapid drying of the soap after use. The holder includes a downwardly and forwardly inclined trough with at least one up-standing retaining flange. A bar of soap resting on the holder has only four points of minimum contact between the bar of soap, the holder and the retainer with the remainder of the bar surface spaced from the holder and retainer for rapid drying.

A further object of the present invention is the provision of a novel soap holder that provides for the least possible soap scuff-off or erosion during use. As the holder contacts the soap at four minimal areas, the possibility of soap scuff-off onto the holder is minimized.

Additionally, the holder with or without the soap resting thereon may be dipped into or passed under the running faucet water for more thorough cleansing and therefore more rapid drying of the soap bar and holder.

10 Further objects are to provide a construction of maximum simplicity, efficiency, economy and ease of assembly, and such further objects, advantages and capabilities as will later more fully appear and are inherently possessed thereby.

DESCRIPTION OF THE DRAWING

FIG. 1 is a perspective view of one form of soap holder positioned at the edge of a shelf of a wash basin.

FIG. 2 is a front elevational view of the holder.

FIG. 3 is a top plan view of the holder.

FIG. 4 is a side elevational view of the holder.

FIG. 5 is a perspective view of a second embodiment of soap holder.

FIG. 6 is a front elevational view of the holder of FIG.

25 5.

FIG. 7 is a side elevational view of the holder of FIG.

5.

FIG. 8 is a top plan view of the holder of FIG. 5.

DESCRIPTION OF THE EMBODIMENTS

Referring more particularly to the disclosure in the drawing wherein are shown illustrative embodiments of the present invention, FIGS. 1 to 4 disclose a soap holder 10 having a base or platform formed of a pair of identical inwardly and downwardly inclined base sections 11 and 12 meeting at a centerline 13 in an obtuse angle forming a trough. Integral with the base sections and extending downwardly at substantially right angles thereto are a pair of depending leg members 14 and 15 extending along the outer edges 16 of the base sections. The rear edge 17 of each leg is longer than the front edge 18, thereby forming a generally trapezoidal configuration so that the holder base is inclined forwardly and downwardly as more clearly seen in FIG. 4.

Formed integral with the base sections 11 and 12 are a pair of soap retaining members or supports 19 and 21 which extend inwardly from the outer edges 16 to terminate short of the centerline 13. The supports 19 and 21 extend upwardly at substantially right angles to the planes of the base sections and, as seen in FIG. 3, are each oriented at an angle to the centerline 13 to form a generally open V-shape. The inner edges 22 of the supports 19 and 21 are spaced from the centerline 13 and each other to allow relatively free flow of liquid down the trough inclined forwardly and downwardly due to the configuration of the legs 14 and 15.

Soap holder 10 is formed of a suitable material, such as polyethylene having a slick, non-stick surface, or of another non-stick non-plastic material. The base sections 11 and 12 and legs 14 and 15, if plastic, could be formed as a flat sheet with the upstanding soap supports 19 and 21 projecting upwardly therefrom and the sheet is bent upwardly at the centerline 13 to form the trough and downwardly at the edges 16 to form the legs, or it could be vacuum formed in one piece. As seen in FIG. 1, the soap bar 23 can be laid flat on the holder or stood up on edge as seen in FIG. 4, with the

holder providing a self-positioning function for the bar of soap. The forward edge 24 of the holder 10 is positioned at or slightly overlapping the edge of the basin shelf or ledge 25 to direct the water and soap suds run-off down the trough and into the basin.

As seen, both inwardly and forwardly downwardly inclined base sections 11 and 12 joined at the centerline 13 form a troughlike structure that directs water and soap suds inwardly to the centerline and then down the trough to spill over the edge 24. Also, the angled position of the supports 19 and 21 enhances the run-off of liquid toward the centerline, and the spaced inner edges 22 allow unencumbered flow down the trough. Also, as seen in FIG. 1, the base sections 11 and 12 and supports 19 and 21 engage and retain the soap at four minimum areas of contact and provide a substantial area of the bar for drying and minimize soap scuff-off.

FIGS. 5 through 8 disclose the preferred embodiment of soap holder 31 which includes a pair of inwardly and downwardly inclined base sections 32 and 33 meeting at a centerline 34 forming a trough. Integral with the base sections and extending downwardly at the outer edges 35 of the base sections and at substantially right angles to the shelf or ledge 36 are a pair of generally parallel depending leg members 37 and 38 having a rear edge 39 which is longer and thereby higher than the front edge 41. Thus, the trough at the centerline 34 is inclined downwardly and forwardly, as clearly seen in FIG. 7, so that there is an unimpeded directed flow of water over the front edge 42 of the holder and into the basin defined by the shelf 36.

Positioned over the trough is a soap retainer or bar 43 formed of a pair of inwardly and downwardly inclined retainer flanges 44 and 45 which are forwardly inclined toward the edges 42 of the holder 31 and joined at a V-joint or obtuse angle 46. The flanges terminate at their outer ends in a pair of support flanges 47 and 48 that are parallel to the leg members 37 and 38. The support flanges 47, 48 are either secured to the base sections' surfaces 32 and 33 at their outer side edges through the slots 50 or vacuum formed infixedly to sections 32 and 33 at the aforementioned points.

As more clearly seen in FIG. 6, the angle of inclination of the retainer flanges 47, 48 is less than the angle of inclination of the base sections 32, 33 so that the lower edges 49 of the retainer flanges are spaced from the upper surfaces of the base sections 32, 33 at the centerline 34, and the spacing decreases towards the outer edges 35. The spacing will aid in the unimpeded directed flow of dripping water and soap suds from the bar of soap and the user.

Soap holders 10 or 31 may be fabricated in either one or two pieces of a suitable material and if non-plastic, with the base sections 32 and 33 and leg members 37 and 38 pre-formed to form the trough at the centerline 34 and the leg members at the edges 35. If the retainer 43 is formed as a separate piece, this piece will be made to form the V-joint 46 between the support flanges 47 and 48 which are then suitably placed into slots 50 punched through the faces of the base sections 32, 33 near their outer side edges. Or the holder made of plastic could also be vacuum formed infixedly as a finished one-piece unit. As in the previous unit, the bar of soap is supported at four small areas with the bar either flat or on edge to promote quick drying and prevent erosion and abrasion of the soap surface.

I claim:

1. A receptacle for a bar of soap comprising a base forming a V-shaped trough downwardly and forwardly inclined with the lower front edge adapted to be positioned in substantial alignment with the edge of a ledge 10 for a basin bowl, said base being formed of a pair of inwardly and downwardly inclined base sections intersecting at a centerline in an obtuse angle to provide the trough, a pair of depending legs of a generally trapezoidal shape integral with the base sections at the outer edges thereof, each leg extending the length of the edge of the base with the height of the rear edge of the legs being greater than the height of the leg front edge, and an upstanding soap retaining means extending substantially across the base and adapted to contact the soap bar at very limited areas, said soap retaining means being slightly spaced from the base at at least the center of the trough and generally inclined toward the centerline thereof to direct flow of water and soap suds into the center of the trough and then automatically downwardly over the lower front edge.

2. A receptacle as set forth in claim 1, wherein said retaining means includes a flange extending upwards at a generally right angle to each base section and extending from adjacent the outer edge of each base section to terminate short of the centerline, said flanges being slightly inclined to direct the flow of water and soap suds into the center of the trough and allow an unimpeded flow of water down the center of the trough and over the lower front edge into the basin bowl.

3. A receptacle as set forth in claim 2, in which each flange is inclined forwardly from its outer edge towards the lower front edge and at an acute angle with the centerline.

4. A receptacle for a bar of soap comprising a base forming a V-shaped trough downwardly and forwardly inclined with the lower front edge adapted to be positioned in substantial alignment with the edge of a ledge for a basin bowl, said base being formed of a pair of inwardly and downwardly inclined base sections intersecting at a centerline in an obtuse angle to provide the trough, and an upstanding soap retaining means extending substantially across the base and adapted to contact the soap bar at very limited areas, said soap retaining means including an upwardly extending unitary bar formed of a pair of flanges intersecting at a centerline in an obtuse angle, and supporting means at the outer edges of the flanges adapted to be secured adjacent the outer edges of the base sections, said bar being slightly spaced from the base at at least the center of the trough and generally inclined towards the centerline thereof to direct flow of water and soap suds into the center of the trough and then automatically downwardly over the lower front edge.

5. A receptacle as set forth in claim 4, in which said bar has a lower edge diverging away from each base section from the outer edge to the trough centerline so that the bar centerline is spaced from the trough centerline with the spacing decreasing toward the outer edges.

6. A receptacle as set forth in claim 5, in which said supporting means comprises a pair of support flanges integral with said soap retaining bar, and a pair of depending legs integral with the outer edges of the base sections, said support flanges being parallel to the depending legs and secured to the base sections adjacent the legs.

7. A receptacle as set forth in claim 6, in which each base section has a slot formed therein adjacent the outer edge thereof, and each support flange has a depending lower edge received into its respective slot.

8. A receptacle as set forth in claim 6, in which said soap retaining bar and supporting means are integral with said base sections.

9. A receptacle for a bar of soap comprising a base forming a V-shaped trough downwardly and forwardly inclined with the lower front edge adapted to be positioned in substantial alignment with the edge of a ledge for a basin bowl, said base being formed of a pair of inwardly and downwardly inclined base sections intersecting at a centerline in an obtuse angle to provide the

trough, and an upstanding soap retaining means extending substantially across the base and adapted to contact the soap bar at very limited areas, said soap retaining means including an upwardly extending unitary retainer bar, and support flanges integral with and depending from said bar and adapted to be secured to said base sections, each base section having a slot formed therein receiving a respective support flange, said bar being slightly spaced from the base at at least the center of the trough and generally inclined toward the centerline thereof to direct flow of water and soap suds into the center and then automatically downwardly over the lower front edge.
